[57] CLAIM

The ornamental design for a simulative toy compact and comb, as shown and described.

DESCRIPTION

FIG. 1 is a front elevational view of a simulative toy compact and comb showing my new design;
FIG. 2 is a left side elevational view thereof;
FIG. 3 is a rear elevational view thereof;
FIG. 4 is a top plan view thereof;
FIG. 5 is a bottom plan view thereof; and
FIG. 6 is a perspective view thereof with the cover in an open position and the comb removed.
